UNITED STATES PATENT OFFICE.

GUSTAVE PERRON, OF PARIS, FRANCE.

ELECTRICALLY-OPERATED AUTOMATIC THROWING-OUT-OF-GEAR MECHANISM FOR BRAIDING MACHINES.

Original application filed June 30, 1922, Serial No. 571,922, and in France July 5, 1921. Divided and this application filed November 24, 1923. Serial No. 676,814.

The present invention has for its object an electrically operated throwing out of gear mechanism for braiding machines in which the breaking of the thread causes through 5 an electric relay, the working of a mechanical device securing the throwing out of gear. The present application is a division of my Patent No. 1,558,039 granted on an application serial No. 571,922, filed June 30, 1922.

10 This device is characterized by the fact that a projection of the throwing out of gear lever of the machine remains in contact with a nose on an intermediary lever and so holds the throwing out of gear lever in the engaged position until, when the thread breaks, a swinging part, released under the action of an electro-magnet, comes on the path of a rotating part of the driving pinion which results in the throwing out of gear 20 lever leaving the engaged position and producing the throwing out of gear of the machine.

Fig. 1 is a fragmentary sectional view illustrating the present improvements; and 25 Fig. 2 is a perspective view on a larger scale showing particularly the automatic stopping mechanism.

For the sake of clearness of the drawing, the spool holder of the spindle is supposed 30 separated from the spindle foot and rotated 90° thereon.

The braiding machine comprises a frame 1 in the shape of a cup on which are mounted the spindle supporting and driving parts. Said parts are driven by a pinion 48 keyed 35 on a vertical shaft 49. On this latter is mounted one of the elements of a claw clutch 50 the other element of which is carried by the device which transmits the driving 40 power to the machine.

On the drawing, the said device comprises two bevel pinions 51 and 52, the latter being secured to a short spindle 53 to which is secured the driving pulley 54.

45 These elements are supported by a suitable part 55 secured to the frame.

The claw coupling 50 is controlled by means of a lever 56 pivoted at 57.

The lever 56 has a stud 66 which acts on 50 a rack or cam 67 of a small lever 68 pivoted at 69 to a part 70 secured to the frame of the machine. A spring 71 has the tendency always to bring back the lever 68 and to keep it in contact with the stud 66. To said

lever 68 is pivoted, at 72, a plate 73 one end 55 73' of which can come within range of a finger 74 provided on the fixed element of the coupling 50 and the other end 73'' of which strikes the part 75 of a lever 76 pivoted at 77 to the part 70. 60

This lever 76 carries a soft iron plate 78 arranged opposite an electro-magnet 79 and is controlled by a spring 80. The lever 56 is always pulled upwards, into the disengaged position, by a spring 81. In the engaged position of the lever 56, the latter is 65 in contact with a spring blade 82 carried by the frame but insulated from the latter.

The conductors of the electro-magnet terminate one at the spring 82 and the other 70 at one of the poles of any desired source of electricity.

A metal ring 83 is mounted above the table 18 of the machine concentrically with the latter, so that the tension levers 31 of 75 the spindles 3 come into contact with the same when the threads break.

This ring is insulated from the mass or body of the machine and connected to the other pole of the source of electricity. 80

The working of the device is as follows:

The electrical device forming relay comprises the ring 83, the electro-magnet 79 and the lever 76, the lightness of which is sufficient to enable it to respond to any impulse 85 from the electro-magnet, however weak said impulse may be.

The throwing out of gear mechanical device comprises the parts 66, 67, 68, 73, 74. It receives the necessary impulse for the 90 throwing out of gear from the driving part 74 of the driving means of the machine the relay device acting simply in order to permit the mechanical device to receive the said impulse. 95

When the thread of one of the spindles breaks, the tension lever 31 is no longer submitted to the action of the thread and the spring 32 pulls violently back said lever 31 and presses it against the circular rim 83. 100 The electric circuit containing the electro-magnet 79 is then closed through the mass of the machine.

The electro-magnet attracts the lever 76 the part 75 of which moves out of the path 105 of the end 73'' of the plate 73. The latter can then turn, the lever arm 73' being much greater in weight than the arm 73'' and the

end 73' is brought opposite the finger 74 which rotates with the driving shaft. This finger strikes 73' and brings about the movement from left to right of the whole 73, 68 5 about the pivot point 69. The part 67 is moved away from the stud 66 and the lever 56 under the action of the spring 81 is turned in such a manner as to produce the disengagement of the claw coupling 50. In 10 this movement, the lever 56 leaves the contact of the spring 82 and the circuit is broken; a cross bar 84 secured to the lever 56 turns the plate 73 and withdraws it from the action of the finger 74.

15 As the current has been broken by 56 going away from the spring 82, the spring 80 draws back the lever 76 to the position shown on the figure, the part 75 being ready for locking the part 73'' of the lever 73.

20 If, after having repaired the thread, the machine is thrown into gear again, the lever 73 resumes the position shown in the figure in which 73'' is locked on the nose 75 of the lever 76 and at the same time the lever 25 56 is locked by the nose 67 of 68 acting on the stud 66.

This device has the advantage that it acts immediately, no matter what the speed of the machine may be. In fact the sensitivity 30 of the lever 76 is such that, as short as may be the contact of the lever 31 with the ring 83, the attraction of the electro-magnet on this lever is sufficient for producing the unlocking of 75 from 73'' as the said 35 73'' exerts on the part 76 of the lever 75 only a light pressure independent from the mass of the heavy parts 50 and 56 of the machine which are to move when the throwing out of gear takes place.

40 Moreover, as soon as the throwing out of gear is produced, the circuit is broken through the separation of 56 and 82, which allows the lever 76 to resume its prior position and to automatically secure the positioning of the throwing out of gear parts 45 for a further operation.

It is also to be noticed that the necessary power for the disengagement of the stud 50 66 from the projection 67 is furnished by the part 74 of the driving mechanism itself, so that whatever may be the strength of the 55 spring 81 forcing 66 against 67, the disengagement will be always secured, the power producing said disengagement being itself proportional to the driving of the machine.

What I claim is:

1. In a braiding machine, in combination, a driving member, a driven shaft, a clutch adapted to connect said member to said shaft, a lever engaging said clutch and biased to move it to unclutching position, a latch normally holding said lever and clutch in cluching position, a normally inoperative connection between said driving member and latch, a normally deenergized elec-

tro-magnet controlling said connection, and means controlled by the breaking of a thread supplied to the machine for closing the circuit of the electro-magnet, whereby upon energization of said magnet the latch is connected to said driving member and is operated thereby to release said lever and permit it to move the clutch to unclutching position. 70

2. In a braiding machine, in combination, a driving member, a driven shaft, a clutch adapted to connect said member to said shaft, a lever engaging said clutch and biased to move it to unclutching position, a pivoted latch engaging said lever and holding it in cluching position against the action of its 80 biasing means, a finger pivoted to the free end of said latch, a cam projection on said driving member, said finger adapted to extend into the path of said projection, means normally holding said finger out of said 85 path, an electromagnet adapted when energized to release said finger, and means controlled by the breaking of a thread supplied to the machine for closing the circuit of said magnet, whereby when a thread 90 breaks the magnet is energized and the finger is released and comes into the path of said projection which engages the finger and positively moves the latch from engagement with the lever, the latter moving under the 95 influence of its biasing means to unclutching position.

3. In a braiding machine, in combination, a driving member, a driven shaft disposed vertically, a clutch member slidable on said vertical shaft adapted to clutch the latter to the driving member, a hand lever having one end engaging said clutch member and tending to rotate on its axis in a direction to disengage said member from the driving member, an arm pivoted at its upper end and having a shoulder engaging over a projection on said lever to hold the lever in cluching position, a finger pivoted intermediate its ends to the lower end of said arm and having one end projecting in proximity to said driving member, an arm pivoted at its upper end and having its lower end engaging over the other end of said finger to hold said finger out of the path of a cam projection on said driving member, an electromagnet having an armature fixed to said last mentioned arm, and means for closing the circuit of said electro-magnet upon breaking of the thread supplied to the machine, said hand lever having a member attached thereto extending under said finger, whereby when said lever after having been released by the energization of the magnet is restored to cluching position the finger 110 will be raised out of the path of the cam projection. 115

In testimony whereof I affix my signature.

GUSTAVE PERRON.
